(57) CLAIM

The ornamental design for a divided coco planter liner, as shown and described.

DESCRIPTION

FIG. 1 is a front perspective view of the divided coco planter liner according to the invention;

FIG. 2 is a top view of our design;

FIG. 3 is a bottom view of our design; and,

FIG. 4 is a front elevation view of our design, the right side, left side, and rear elevations being identical thereto.
